CLAIM

The ornamental design for an applicator tip for a cosmetic container, as shown and described.

DESCRIPTION

FIG. 1 is a perspective view of an applicator tip for a cosmetic container showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged left side view thereof;

FIG. 9 is an enlarged view in the portion within the dot-dot-dashed line box 9 in the FIG. 1 thereof;

FIG. 10 is an enlarged cross-sectional view along the line 10-10 in the FIG. 2, in the portion within the dot-dot-dashed line box 10' in the FIG. 2 thereof;

FIG. 11 is an enlarged cross-sectional view along the line 11-11 in the FIG. 6, in the portion within the dot-dot-dashed line box 11' in the FIG. 6 thereof; and,

FIG. 12 is an enlarged view in the portion within the dot-dot-dashed line box 12 in the FIG. 7 thereof.

The broken lines shown represent portions of the claimed design and form no part of the claimed design.

The dot-dashed lines which define the bounds of the claimed design form no part of the claimed design.

The dot-dot-dashed lines indicate the portions shown in enlargement views and form no part of the claimed design.
